UNITED STATES PATENT OFFICE.

SILVANUS F. VAN CHOATE, OF NEW YORK, N. Y.

DESIGN FOR A COMBINED STREET-LAMP AND REFLECTOR.

SPECIFICATION forming part of Design No. 13,462, dated November 28, 1882.

Application filed June 1, 1881. Term of patent 14 years.

To all whom it may concern:

Be it known that I, SILVANUS F. VAN CHOATE, a citizen of the United States, residing at New York, in the county of New York 5 and State of New York, have invented and produced a new and useful Design for Combined Lamp and Reflector for Streets and other Locations, of which the following is a specification, reference being had to the accompanying drawing, forming part thereof.

The drawing is an elevation of my design.

A represents the post or support upon which is mounted the lamp or light proper, surrounded by a transparent globe, B, of spherical or 15 spheroidal form. This globe is supported upon sleeve C at the top of the post. The light itself is here shown as an electric light. Directly upon or immediately above the top of the globe is an inverted conical reflector, G, 20 above which is a conical hood or roof, H, of about the same inclination as the reflector, the lower edge of which hood joins the upper edge of the conical reflector. At the point of junction is an ornamental border or crown, I,

of any desired configuration. The whole is 25 surmounted by an ornamental finial, L, terminating in a representation of a flame, M. The pillar or finial L may be somewhat varied in its configuration without changing the general appearance of the lamp or departing 30 from the spirit of the invention.

The design of the ornamental crown I may be largely varied.

What I claim as my invention is—

1. The design consisting of the globe B, the 35 superposed inverted conical reflector, and the conical hood H, all as shown and described.
2. The design herein shown, consisting of the globe, the inverted conical reflector G, the conical hood H, and the ornamental band or 40 crown I.
3. The design for a lamp and reflector, as described and shown in the drawing.

SILVANUS F. VAN CHOATE.
